UNITED STATES PATENT OFFICE.

DUDLEY H. ROBEY, OF INDIANAPOLIS, INDIANA.

INTERNAL-COMBUSTION ENGINE.

1,233,918.

Specification of Letters Patent. Patented July 17, 1917.

Application filed March 6, 1916. Serial No. 82,412.

To all whom it may concern:

Be it known that I, DUDLEY H. ROBEY, a citizen of the United States, residing at Indianapolis, Marion county, and State of Indiana, have invented and discovered certain new and useful Improvements in Internal-Combustion Engines, of which the following is a specification.

My invention relates to internal combustion engines and its object is to provide a valve mechanism of a construction that will produce a minimum amount of friction, that will prevent carbonization of the valve in its seat; that will avoid the necessity of regrinding the valves; that will permit of the employment of ports of large area; that will provide for a positive driving action of the valves and that will obtain the advantages of the sleeve valve type of motor while at the same time greatly reducing the friction due to such type as heretofore employed, obviating the necessity of the careful machining of the valve and also providing a straight line driving connection for the valves and enabling the necessary close fit between the valve and its wall to be obtained by means of rings instead of by direct contact between the valve and such wall and also enabling the surface of the valve to be protected against the gases, and the heat and flame of the explosions.

With these objects and others in view, my invention is embodied in preferable form in the construction and arrangement hereinafter described and illustrated in the accompanying drawings.

In these drawings, Figure 1 is a vertical sectional view through an explosion cylinder crank case and an intake and an exhaust valve for such cylinder, the section being taken through the ports; Fig. 2, a top plan view showing a part thereof in section on the line 2-2 of Fig. 1; Fig. 3, an enlarged vertical section on the line 3-3 of Fig. 2; and Fig. 4, an enlarged vertical section on the line 4-4 of Fig. 2.

Referring to the drawings, 1 indicates the cylinders of a four-cycle internal combustion engine, the improvements herein being shown as applied to a four cylinder engine, although it will be obvious that they are equally applicable to an engine having a greater or less number of cylinders. 2 indicates the piston in the explosion cylinder, 3 the connecting rod and 4 the main

shaft. On this main shaft is a gear 5 adapted to mesh with gears 6 and 7 carried by shafts 8 and 9 respectively, which shafts are provided with suitable cranks to which are pivoted a series of connecting rods 10 and 11 on each side of the main shaft.

Each rod 10 is pivoted at its upper end to a hollow sleeve valve 12 which valve is mounted in a cylinder 13, preferably formed as part of the casting which includes the explosion cylinders. The sleeve valve 12 constitutes the common exhaust valve for a pair of cylinders and controls the exhaust from each cylinder in the order of the usual succession of operations of the respective cylinders according to the usual time of explosions therein. To this end the shaft 8 makes one revolution to two revolutions of the main engine shaft.

The sleeve valve is provided on its periphery at suitable intervals with ordinary piston packing rings 14 which bear against the wall of the cylinder in which the valve is mounted and the use of which is rendered possible owing to the separation of the valve from the main explosion chamber and the fact that the gases pass through the wall of the valve at an angle to the longer axis thereof and that the valve is driven from a center immediately below the center of the valve.

Projecting downwardly within the valve is a fixed pipe or sleeve 15 between the outer surface of which and the wall of the valve cylinder 13 the valve is adapted to slide, by which arrangement the surface of the valve throughout its length is protected from the direct contact of the flame and heat from the explosion chamber and protected for all of its surface except that part adapted to close the ports from the contact of the exhaust gases themselves.

The valve is provided in its wall with a single circumferential port 16 which is adapted to register with an upper exhaust port 17 formed in the wall of the valve cylinder in that segment of the circle of said cylinder which is substantially opposite the center of the point between the explosion cylinders of each pair, and this port communicates by a downwardly arched and laterally curved passageway 18 with the upper end of one of the explosion chambers. A similar lower exhaust port 19 is provided in the wall of the valve cylinder

and communicates by an upwardly arched and laterally curved passageway 20 with the upper end of the explosion chamber of the other cylinder of said pair.

5 In the exhaust pipe or casing 15 are formed upper and lower exhaust ports 21 and 22 respectively which are directly opposite and adapted to register with the ports 17 and 19 respectively of the valve cylinder.

10 The single port 16 of the sleeve valve is adapted to establish communication alternately between the ports 17 and 21 and 19 and 22 respectively for the purpose of permitting the escape of the exhaust in due

15 succession and alternately from the cylinders of one of the pairs of explosion units, whereby the exhaust gases will be led laterally through the wall of the sleeve valve into the chamber of the exhaust pipe. The

20 exhaust pipe or casing 15 communicates at its upper end with an exhaust manifold 23.

On the opposite side of the pair of cylinders is mounted an inlet sleeve valve cylinder 25 having therein an inlet sleeve valve

25 26 provided with packing rings 27 and adapted to reciprocate between the wall of said cylinder and a cylindrical protective intake conduit pipe 28 which communicates at its upper end with an intake manifold 29,

30 the construction and operation of said intake valve being identical with that of the exhaust valve above described. This intake valve is also common to both cylinders of a pair and is provided with a single port

35 which is adapted to be brought successively into register with upper and lower pairs of intake ports formed in the cylinder wall and intake pipe respectively, whereby intake communication is established alternately with each of the explosion cylinders

40 of a pair of such units.

With the above construction, a single intake valve and a single exhaust valve are employed for each pair of cylinders, and

45 these valves are protected against the heat and flame in the explosion cylinders owing to the fact that they are separated by their cylinder walls from such explosion cylinder, and that the gases are forced to travel

50 laterally or horizontally through the ports into the inner protecting casing. It is also

clear that the ports may be made of large area and such area may be increased beyond that shown in the drawings by further in-

55 creasing the vertical length of the ports and increasing the length of stroke of the valve rods.

The valves are timed to operate in accordance with the usual order of succession of

60 the firing, exhaust, intake and compression operations of the respective cylinders in a manner well known.

Having thus described my invention, what I claim is:

65 1. In an internal combustion engine, in

combination with a pair of explosion cylinders, a reciprocable sleeve valve common to said cylinders, a cylinder common to and separate from the explosion cylinders in which separate cylinder said valve is mounted for reciprocation, a pair of vertically spaced ports in the valve cylinder, one directly above and in line with the other adapted to respectively communicate with said explosion cylinders, said valve having a single port adapted to alternately register with said cylinder ports.

2. In an internal combustion engine, in combination with a pair of explosion cylinders, a sleeve valve common to both cylinders, a valve cylinder separate from said cylinders and parallel thereto and in which said valve is mounted for reciprocation, said valve cylinder having two ports the centers of which are opposite the center line between the two cylinders and which are spaced apart vertically with one directly above and in line with the other and communicating respectively with said explosion cylinders by passageways respectively

70 downwardly and upwardly arched and laterally curved, and said valve having a single circumferential port also opposite said center line adapted to communicate alternately with said ports leading to the explosion chambers.

3. In an internal combustion engine, in combination with a pair of explosion cylinders, a reciprocable sleeve valve common to both cylinders, a valve cylinder separate from the explosion cylinders and extending parallel thereto in which said valve is mounted, a fixed hollow gas receiving and conveying tube extending within and fitting against said sleeve valve, said valve cylinder wall and tube each having a vertically spaced pair of respectively registering ports, all in alignment and opposite the center line between the cylinders, adapted to communicate with the respective explosion cylinders, said valve having a single circumferential port adapted to alternately register with said pairs of ports, packing rings on the outer periphery of said sleeve valve and positive driving means for said valve having the driving center thereof in line with the center of the valve.

4. In an internal combustion engine, in combination with a pair of explosion cylinders, a single exhaust-controlling sleeve valve common to both explosion cylinders, a single common inlet-controlling sleeve valve, separate cylinders for said valves located on opposite sides of the explosion cylinders and between their medial lines, each of said valve cylinders having a pair of vertically spaced ports communicating with respective explosion cylinders at the same relative points and having passageways respectively downwardly and upwardly arched and lat-

erally curved to establish such communication, each of said valves having a single port, and all of said ports being in vertical alinement and having their centers opposite to the vertical center line between the explosion cylinders.

In witness whereof, I have hereunto set

my hand and seal at Indianapolis, Indiana, this 4th day of March, A. D. nineteen hundred and sixteen.
